UNITED STATES PATENT OFFICE

EDWARD N. MACKLEY, OF NEWCASTLE-UPON-TYNE, ENGLAND.

REMOVABLE LINER FOR CENTRIFUGAL PUMPS.

Application filed February 25, 1924. Serial No. 694,961.

To all whom it may concern:

Be it known that I, EDWARD NORMAN MACKLEY, a subject of the King of Great Britain and Ireland, residing at 55 Win-
5 grove Road, in the city and county of New-
castle-upon-Tyne, England, have invented
certain new and useful Improvements in Re-
movable Liners for Centrifugal Pumps, of
which the following is a specification, refer-
10 ence being had therein to the accompanying
drawing.

This invention relates to centrifugal
pumps of the kind having a fixed outer cas-
ing, usually of cast iron, fitted with a re-
15 movable liner which constitutes the volute-
shaped guide passage surrounding the im-
peller or wheel, said liner having portions
extending inwards on each side of the im-
peller in close proximity thereto. The ob-
20 ject of my invention is to provide an im-
proved construction of removable liner of
this type. A liner in accordance with this
invention is characterized in that the side
25 portions provide bearing surfaces for both
the eye portion and the hub of the impeller,
said side portions being axially withdraw-
able with the liner and the impeller from the
outer casing. The inwardly-extending por-
30 tions may be separate from the volute-shaped
guide passage, in which case they are at-
tached by external bolts around their pe-
ripheries to flanges around said volute-
shaped guide passage; or the volute-shaped
35 guide passage may be made in halves each
half having an integral inwardly-extending
portion, said halves being connected together
by external bolts passing through abutting
peripheral flanges around the liner.

I will fully describe my invention with
40 reference to the accompanying drawings
wherein Figure 1 is a vertical section of a
centrifugal pump fitted with a liner having
inward extensions in accordance therewith;
and Figures 2 and 3 are a vertical section
45 and a side elevation respectively of the liner
removed from the casing. Figures 4, 5 and
6 are similar views to Figs. 1, 2 and 3 re-
spectively illustrating a modified construc-
tion.

50 Referring to the drawings, in the example
illustrated in Figs. 1, 2 and 3, *a* is the re-
movable liner which is shaped as usual to
form the volute-shaped casing or guide pas-
sage for the impeller *b* of the pump. In
55 this example, the liner is in one integral
part and is not positively secured to the

outer casing *c*. *d*, *d* are the inward exten-
sions of the liner which are in the form of
separate rings of suitable shape secured by
external bolts *e* around their peripheries to 60
flanges *f* around the liner. The extensions
d are in close proximity to and partially en-
close the impeller *b*. The inner edge of one
of the side portions *d* of the liner provides
a bearing surface *g* for the eye portion of 65
the impeller *b* and an internal shoulder
around the other side portion provides a
bearing surface *h* for a laterally-projecting
flange *m* around the hub of the impeller, the
inner edge *d'* of the latter side portion en- 70
gaging an internal flange *c'* of the outer cas-
ing. The space around the impeller is thus
restricted and fluid leaking between the liner
and the impeller is confined to said restricted
space. The side portions *d'* form the only 75
bearing surfaces for both the eye and the
hub of the impeller. As the extensions *d*
become worn they can be readily removed
and new extensions fitted, wear on the outer
cast iron casing *c* being entirely eliminated. 80

In the modified construction illustrated in
Figs. 4, 5 and 6, the liner *a* and its exten-
sions *d* are made in integral halves con-
nected together by external bolts *j* passing
through abutting peripheral flanges *k* 85
around the liner. Otherwise this construc-
tion is exactly similar to that shown in Figs.
1, 2 and 3.

It will be seen that the bolts *e* and *j*,
being outside the water passages, are not 90
liable to erosion due to the grit in the water.
Moreover the liner and its extensions are
not bolted to the outer casing *c* and can be
readily withdrawn axially therefrom with
the impeller when the cover *n* of the casing 95
is removed.

What I claim as my invention, and desire
to secure by Letters Patent is:—

1. A centrifugal pump comprising an
outer casing and an impeller, a removable 100
cover for said casing, and a removable liner
within said casing comprising a volute-
shaped guide passage surrounding the im-
peller of the pump and inwardly-extending
portions on each side of the impeller in close 105
proximity thereto, said side portions form-
ing the only bearing surfaces for both the
eye portion and the hub of the impeller and
being axially withdrawable with the liner
and the impeller from the outer casing. 110

2. A removable liner for a centrifugal
pump comprising a volute-shaped guide pas-

sage surrounding the impeller of the pump, inwardly-extending portions on each side of the impeller in close proximity thereto, the inner edge of one of said side portions forming the bearing for the eye portion of the impeller, a laterally projecting flange around the hub of the impeller, an internal shoulder around the other of said side portions forming the bearing for said laterally projecting flange and an internal flange on the outer casing of the pump, the inner edge of the latter side portion engaging said internal flange, said side portions being axially withdrawable with the liner and the impeller from the outer casing.

3. A removable liner for a centrifugal pump comprising a volute-shaped guide passage surrounding the impeller of the pump, flanges around said guide passage, separate

inwardly-extending portions on each side of the impeller in close proximity thereto, external bolts around the peripheries of said side portions attaching them to the flanges of said guide passage, the inner edge of one of said side portions forming the bearing for the eye portion of the impeller, a laterally projecting flange around the hub of the impeller an internal shoulder around the other of said side portions forming the bearing for said laterally projecting flange and an internal flange on the outer casing of the pump, the inner edge of the latter side portion engaging said internal flange, said side portions being axially withdrawable with the liner and the impeller from the outer casing.

In testimony whereof I affix my signature.
EDWARD N. MACKLEY.
